[57] ABSTRACT

A universal retaining ring tool that is shiftable between internal and external modes of operation. The tool includes a pair of pivotally connected handles, a pair of jaw members selectively coupled to the handles by a latching arrangement including two transversely slidable latch members. In one position of the latch members one handle member is coupled to one jaw member and the other handle is coupled to the other jaw member. When the latch members are switched, the one handle is coupled to the other jaw member and the other handle is coupled to the one jaw member. Removable tips are secured to each jaw member by an associated clamping plate that includes a corner that diverges from the overall plane of the clamping plate towards the associated jaw member. The fastener for securing the clamping plate is critically located so that a positive clamping force is exerted on the tip in a region where it enters the jaw. A lock lever is pivotally connected to one of the handles and provides for a locking position engaging the spring and coacting surface to lock the tool in a closed position. Where a plurality of coacting surfaces and a ratchet lever are included, a ratchet is provided which locks the relative position of the handles as they are squeezed.

RETAINING RING TOOL

DESCRIPTION

This application is a continuation-in-part of prior U.S. application Ser. No. 669,672 filed Nov. 8, 1984 under the title Retaining Ring Tool.

TECHNICAL FIELD

The present invention relates generally to hand tools and in particular to apparatus for removing and installing resilient retaining rings.

BACKGROUND ART

Resilient retaining rings such as "snap rings", "E-rings" and "C-rings" are employed to maintain the position of elements on a shaft or to maintain the position of elements within a bore. To facilitate removal and installation, some rings are formed with apertures at terminating ends by which a ring is engaged and then either expanded or contracted by a suitable tool.

Retaining rings are supplied as "internal" or "external". The external type are usually used to retain elements such as bearings, gears, or pulleys on shafts. An external ring normally engages an annular groove formed in a shaft to inhibit axial movement of a shaft mounted element. The external-type ring is installed by expanding the ring until its internal diameter is greater than the shaft diameter.

The internal type of retaining ring is used to retain an element such as bearings or shafts, within a bore. In order to install a ring it is contracted in order to pass into the bore and then allowed to expand to engage an internal groove formed around the bore.

Normally tools for installing and removing external and internal type retaining rings are substantially different. In the case of external rings, the tool must expand the ring to increase its internal diameter in order to clear a shaft whereas in the case of internal rings, the tool must contract the ring in order to decrease its external diameter to enable the ring to clear a bore. For this reason, retaining ring pliers are supplied as single purpose "external" and "internal" types. These single purpose pliers are each intended to remove or install one type of ring only and therefore a mechanic is required to have both types of pliers if he is to remove both external and internal rings.

In the past, dual purpose retaining ring pliers have been suggested or tried. In one proposed construction, the tool included a single pivot shaft, but two pivot holes. When the shaft was placed in one pivot hole, the tool acted as an external retaining ring plier and when placed in the other hole, the tool became an internal retaining ring plier. In order to switch between internal and external functions, the tool required disassembly.

In another construction, one handle of the retaining ring plier is articulated intermediate a jaw pivot point and the end of the handle. The handle also includes a movable link which in one position locks the one handle to prevent articulation and causes the tool to act as an internal type retaining ring plier. The link is movable to another position which allows articulation of one handle with respect to the jaw pivot point and causes the tool to act as an external retaining ring tool. The problem with this latter construction is that movement of the link changes the mechanical advantage so that the force needed to operate the tool is different when it was used

in the "internal" mode compared to the "external" mode.

In still another construction, a pair of jaws is selectively engaged with a pair of handles utilizing axially movable pins. It is believed that the suggested construction is expensive to manufacture and changing from "internal" to "external" functions is cumbersome since movement of the relatively small pins is difficult and requires a separate tool to effect movement in the pins.

- 5 Many commercially available and proposed retaining ring tools include a removable tip. Clamping members associated with each jaw typically clamp the tip in a groove formed in the jaw and/or the clamping plate. The mounting arrangements must not only secure the
10 longitudinal position of a tip, but in the case of angled tips, must also restrain or inhibit rotation of the tip with respect to the jaw. It has been found that with some prior art clamping arrangements insufficient clamping force is exerted on the tips to inhibit rotation when the tip is subjected to high retaining ring forces. Rotation of the tip within its groove can often damage not only the tip but the tool itself in addition to causing frustration to the user.

DISCLOSURE OF INVENTION

25 The present invention provides a new and improved hand tool for removing and installing both external and internal retaining rings. The tool is easily switched between internal and external modes of operation and the
30 mechanical advantage is the same for both modes.

In the preferred embodiment, the hand tool comprises a pair of pivotally connected handles and a pair of jaw members selectively couplable to the handles by a latching arrangement including transversely slideable
35 latch members. The latch members are movable between two positions. In one position one handle is coupled to one jaw member and the other handle is coupled to the other jaw member. In a second position, the one handle is coupled to the other jaw member and the other handle is coupled to the one jaw member. In one position of the latch members, the tool operates as an internal retaining ring tool and in the other position the tool operates as an external retaining ring tool.

40 In the preferred construction, each handle includes a
45 jaw driving section or boss on one end. Each jaw driving section includes two segments, each segment including structure couplable with one of the jaw members or plier parts by operation of the associated latch member.

Each latch member is slidably movable between two
50 positions. In one position, the member interconnects structure on one segment of one handle with one jaw member. In the other position, the latch member interconnects the other segment of the one handle with the other jaw member. The other latch member provides a
55 similar function and selectively couples either the one segment of the other handle with the other jaw member or the other segment of the other handle with the one jaw member. In operation, the latch members are concurrently moved between the two positions so that each
60 jaw member is always coupled to one of the handles.

In the illustrated embodiment, the engagement structure on the jaw driving sections of the handles and the jaw members comprise peripheral slot-like recesses. Each latch member includes a prong disposed in a plane
65 that diverges from a rotational plane of the tool as defined by a pivot axis for the handles. In the preferred embodiment the prong is disposed in a plane substantially orthogonal to the rotational plane and is sized to

slidably fit within a recess. The depth of prong is dimensioned such that adjacent recesses in a jaw and a jaw driving segment are coengaged.

According to the exemplary embodiment, both latching members are shiftable when the recesses in the handles and the jaws are aligned. The prongs define adjacent abutment surfaces by which the members are concurrently shifted from one position to the other. In this way, changing from the internal to the external mode of operation is easily accomplished.

According to a feature of the invention, a ratchet mechanism is included which locks the relative position of the handles as they are squeezed when contracting or expanding a retaining ring. With this feature, installation of either an external or an internal retaining ring is facilitated since the ratchet mechanism prevents the handles from reopening due to the tension exerted by a retaining ring held by the jaws. In the preferred embodiment, the ratchet mechanism includes a lever mounted to one of the handles which is engageable with teeth formed on the jaw driving section of the other handle. The lever is spring loaded towards engagement with the teeth so that as the handles are squeezed a ratchet pawl on the lever engages successive teeth preventing the handles from pivoting outwardly.

According to another feature of the invention, a locking mechanism is featured for locking the tool in a closed position. The locking mechanism includes a lever pivotally mounted on one of the tool handles for movement between locked and unlocked positions. The lever is selectively engageable with the biasing spring, which acts to urge the tool handles apart. As the handles are compressed to a tool release position, the lever may be pivoted into engagement with a coacting surface of the boss or jaw driving section and the biasing spring to the locked position. The locking mechanism also provides for automatic disengagement of the lever from the locked position. In the preferred embodiment, the lever is released from the locked position upon compression of the tool handles to the release position. As the lever is disengaged from the end surface or coacting surface, the biasing spring acts against the lever, automatically pivoting the lever out of the locked position. Use of this locking feature prohibits movement of the jaws and handles during storage.

In the preferred construction, unintentional disengagement of the device is also unlikely upon movement or contact with other items due to the location and configuration of the lever, which is positioned to avoid interference with other items during storage.

According to another feature of the invention, each jaw member includes a clamping arrangement for securing a removable tip configured to engage an aperture in the retaining ring. The clamping arrangement includes a plate member fixed to the jaw by a suitable fastener. The plate includes a portion, preferably a corner, bent towards the jaw so that as the plate is fastened to the jaw, a greater clamping force is exerted near the end of the jaw from where the tip protrudes. The disclosed arrangement provides an enhanced securement of the tip to the jaw.

In the preferred embodiment, the segments defined by the jaw driving sections of each handle are disposed in offset planes. One segment of each jaw driving section defines a pivot aperture defined in part by an annular wall. The segments are disposed in spaced, parallel planes and are joined together by a bridging section. When the handle members are assembled, the segments

of the handle members are at least partially interleaved such that a portion of the annular wall defined by a segment on one handle rotatably abuts an arcuate surface on the adjacent segment of the other handle. The bridging sections that join the respective segments also define stops which limit the outward movement of the handles.

In the disclosed and illustrated embodiment, the handles, jaw members and latch members are all formed from stampings yielding in extremely useful but relatively inexpensive retaining ring tool. The tool eliminates the need for separate internal and external retaining ring pliers and is easily switchable between external and internal operating modes.

Additional features will become apparent and a fuller understanding obtained by reading the following detailed description made in connection with the accompanying drawings.

BRIEF DESCRIPTION OF DRAWINGS

FIG. 1 is a plan view of a retaining ring removal and installation tool constructed in accordance with a preferred embodiment of the invention;

FIG. 2 is a side view of the tool;

FIG. 3 is an exploded view of the tool;

FIG. 4 is a plan view of the lock lever in use on a retaining ring tool, with jaws removed for clarity of illustration where the solid line drawing shows the tool in the closed position and the broken line drawing demonstrates the tool release position, and

FIG. 5 is a plan view of the tool of FIG. 4 in the open position and the lock lever in the unlocked position.

BEST MODE FOR CARRYING OUT THE INVENTION

FIG. 1 illustrates the overall construction of a hand tool for removing and installing internal or external type resilient retaining rings. The tool comprises a pair of operator actuated handles 10, 12 each defining respective grip portions 10a, 12a. In the illustrated embodiment, the grip portions 10a, 12a are covered by plastic grip coverings 14. The handles 10, 12 are squeezed by an operator in order to either open or close a pair of jaw heads 16, 18, depending on the operating mode of the tool. The jaw heads define respective jaws 16a, 18a that each removably mount a conventional ring engaging tip 19 engageable with an aperture formed on a retaining ring (not shown). As is known in the art and shown in FIG. 2 various tip configurations 19, 19' are available to accommodate a multitude of rings and ring applications. The jaw heads each include an associated clamp plate 20 by which the tips 19 are clamped to the jaws 16a, 18a. A threaded fastener 21 secures the plate 20 to the respective jaw. Referring to FIG. 3, a channel-like groove 22 is formed in each of the jaws 16a, 18a which is sized to receive the tip 19. A companion groove 23 is formed in each clamp plate 20 and overlies the groove 22 formed in the jaw when the plate 20 is mounted in position.

In one mode of operation, the tool is adapted to manipulate internal retaining rings and in this mode, squeezing the handles produces movement in the jaw heads 16, 18 and associated tips 19 towards each other. In the "external" mode, squeezing the handles produces outward movement of the tips 19 thus enabling the jaw heads to expand an external retaining ring. It should be noted that in FIG. 1, the tool is shown in its "internal" mode with the handles 10, 12 shown in their squeezed

positions. The phantom lines indicate the positions assumed by the handles 10, 12 and the jaw heads 16, 18 when the handles are released. When the tool is switched to the "external" mode, squeezing the handles 10, 12 causes the jaw heads 16, 18 to separate and assume the open position indicated by the phantom lines.

In accordance with the invention, the tool includes a latching mechanism indicated generally by the reference character 24 in FIG. 1, by which the tool is switched between "internal" and "external" modes of operation.

Referring also to FIG. 3, the handles 10, 12 each include a respective jaw driving section or boss section 26, 28, 26', 28'. As will be explained, slideable bar-like latch members 30, 31 selectively couple the jaw heads 16, 18 to the jaw driving sections 26, 28 of the handles 10, 12.

As seen best in FIG. 3, the jaw driving sections 26, 28 comprise two segments disposed in spaced planes. In particular, the jaw driving section 26 includes a first segment 26a which merges with its associated handle 10. A second segment 26b is arcuate and extends in a plane disposed below the plane of the segment 26a. A bridging section 26c joins the two segments. The jaw driving section 28 includes similar segments and in particular includes a segment 28a that merges with the handle 12 and a segment 28b disposed below the plane of the segment 28a. A bridging section, indicated generally by the reference character 28c in FIG. 3 joins the segments 28a, 28b.

The segments of the jaw driving sections 26, 28 are configured to partially interleave with each other, as seen in FIG. 3. The segments 26a, 28a when assembled are disposed in a substantially common plane. The segments 26b, 28b are also disposed in a substantially common plane that is spaced below (as viewed in FIG. 3) the plane of the segments 26a, 28a.

The segment 26a of the section 26 defines a pivot aperture 32. A semi-annular wall 34 also forms part of the segment 26a and at least partially defines the pivot aperture. The segment 28a of the handle 12 defines an arcuate wall 36 which abuttably engages the aperture wall 34. The segment 28b of the handle 12 defines a similar pivot structure which is engaged by a semi-annular wall (not shown) forming part of the segment 26b (indicated generally by the reference character 38). The arcuate surfaces 36, 38 and annular wall segments 34 provide bearing surfaces between the interleaved jaw driving sections 26, 28 of the handles 10, 12.

As seen in FIG. 3, the segment 28a of the jaw driving section 28 defines a gap 40 between an end surface or coacting surface 42, 42' and the bridging section 26c. This gap defines the limits of outward movement of the handles 10, 12. It should be apparent as the handles are separated, the gap defined between the bridging section 26c and the end surface 42 diminishes. Eventually, the end surface 42 abuttably contacts the bridging section 26c preventing further outward movement of the handle members. A similar gap is defined between an end surface or coacting surface defined by the segment 26b and the bridging section 28c.

Each of the segments includes a peripheral recess disposed 180° apart. In particular, the segments 26a and 26b include respective notches or latch member engaging surfaces 46a, 46b, 46a', 46b'. The segments 28a, 28b also define respective notches or latch member engaging surfaces 46a, 46b, 46a', 46b'. The jaw heads 16, 18 and handles 10, 12 are pivotally secured together by a

pivot pin 50 that extends through apertures 54 formed in the jaw heads and through the apertures 32 defined by the pivot structure in each of the jaw driving sections 26, 28. The pivot pin 50 may take the form of a rivet, shoulder screw or other known fastener. When the pivot pin 50 is secured, the handles 10, 12 as well as the jaw heads 16, 18 are pivotally movable with respect to each other.

The jaw heads 16, 18 each include a circular recess 60 which is axially aligned with the associated pivot apertures 54. Each recess 60 is interrupted by a pair of aligned passages 64 or laterally extending guide surfaces 64' which together define a guideway for an associated latch member 30, 31.

The latch members 30, 31 are operative to couple an associated jaw head with one of the jaw driving segments 26, 28. Each latch member is defined by a pair of spaced prongs 70, 72 joined by an elongate web 74. The prongs 70, 72 are disposed in planes that diverge from the rotational plane of the tool as defined by the pivot 50. Preferably the prongs are oriented at substantially 90° with respect to the rotational plane. The web includes an offset intermediate section 74a defining a clearance gap for the pivot pin 50. The gap defines the transverse limits of motion for each latch member 30, 31. Outer web sections 74b disposed on either side of the intermediate section 74a are sized to be slidably received by the aligned passages 64 formed in the associated jaw head. When assembled, the pivot pin 50 for securing the assembly extends through the gap defined between the guide sections 74b. The latch members 30, 31 are sized so that at their extremes of movement one of the prongs 70, 72 of each latch member 30, 31 is received in one of the notch-like recesses 46a, 46b formed in each jaw driving section 26, 28. In the preferred embodiment the line of action for each latch member intersects the pivot axis defined by the pivot pin 50.

For example, when the lower latch member 30 (as viewed in FIG. 3) is moved rearwardly (i.e., movement such that the prong 70 moves toward the pivot) the prong 70 enters the recess 46b in the segment 26b of the jaw driving section 26 forming part of the handle 10. When moved in this position, the prong 70 couples the jaw 16a to the handle 10 so that both move as one.

Similarly, when the upper latch member 31 is moved rearwardly, the prong 70 of the upper latch member moves into the recess 46b of the segment 28a of the jaw driving section 28 forming part of the handle 12 so that the upper jaw head 18 and the handle 12 move as one. It should be apparent that, with the upper jaw 18 coupled to the handle 12 and the lower jaw 16 coupled to the handle 10, movement in the handles towards each other produces converging movement in the jaws 16a, 18a towards each other. Thus, in this position, the hand tool is operative to remove and install internal type retaining rings since squeezing the handles 10, 12 will contract a retaining ring held by the tips 19.

To change the tool to an external mode, the latch members 30, 31 are shifted forwardly, as viewed in FIG. 3, that is, motion in which the prongs 70 move away from the pivot point. In particular, the prong 72 of the lower latch member enters the recess 46b formed in the segment 28b of the jaw driving section 28 and is thus coupled to the handle 12. The upper latch member 31 is moved so that its prong 72 engages the recess 46a in the segment 26a of the handle 10 and thus the upper jaw head 18 is interconnected to the handle 10. With the

latch members 30, 31 in this reversed position, the upper and lower jaws are operatively connected to the handles 10, 12 respectively and squeezing the handles causes the jaws 16a, 18a to separate. In this configuration, the hand tool is operative to remove and install external type retaining rings since squeezing the handles tends to expand a retaining ring held by the tips 19.

In summary, the hand tool is switched between internal and external modes by aligning the recesses 46a, 46b of the jaw driving sections 26, 28 and then concurrently shifting both latch members 30, 31 to cause one set of prongs, either the prongs 70 or the prongs 72 to engage a pair of recesses 46a, 46b of the jaw driving sections 26, 28. In one position, the latch members 30, 31 couple the lower jaw head 16 to the handle 12 and the upper jaw head 18 to the handle 10 whereas in the other position, the lower jaw head 16 is coupled to the handle 10 and the upper jaw is coupled to the handle 12.

According to a feature of the invention, the tip clamps 20 each include a diverging corner 80 which is bent towards the plane of the associated jaw. With this construction, the clamping force exerted by the plate 20 on the tip 19 is directed towards the leading edge 20a of the plate 20 and thus enhances the securement of the tip to the jaw.

In order for it to provide a greater clamping force at the leading edge 20a of the plate 20 the clamping screw 21 is critically located. As seen best in FIG. 1, the centerline of the clamping screw 21 lies on an imaginary line 84 that extends through the center of the diverging corner 80 and point where the tip groove commences at the leading edge 20a of the clamp. In the preferred arrangement, the imaginary line 84 intersects the center of the tip groove. However, the clamping screw may be located on an imaginary line that intersects the tip groove at other than the exact center of the groove and still be encompassed by the present invention. With the disclosed construction, as the clamping screw 21 is tightened, the portion of the clamp plate 20 to the left of the clamping screw 21 (as viewed in FIG. 1) is levered downwardly by the fulcrum action provided by the tip 80a of the diverging corner 80. Consequently, a major portion of the clamping force is exerted on the portion of the tip 19 clamped by the left portion (as viewed in the figures) of the clamping plate 20 thus providing a positive securement of the tip 19 in the region where it enters the groove 23 defined by the clamp plate 20 and the associated head.

In a preferred embodiment, a biasing spring 90 urges the handles apart. According to a feature of the invention, a ratchet mechanism is provided for locking the handles to inhibit separation. The mechanism includes a pivotally mounted ratchet lever 94 pivotally secured to one of the handles. In the illustrated embodiment the ratchet lever 94 is mounted to the handle 10 and includes a tab 95 which engages the spring 90. The spring thus not only biases the handles apart but also biases the lever in a counterclockwise direction (as viewed in FIG. 3). The ratchet lever includes a finger engaging portion 94a which overlies the outside edge of the handle 10. A ratchet pawl 98 is also defined by the lever 94 and located to one side of the pivot opposite the spring engaging tab 95. The pawl 98 is engageable with one of a plurality of coacting surfaces or teeth 100 formed on the periphery of the segment 28b of the jaw driving section 28 that is part of the handle 12. It should be apparent that when the handles are squeezed and the ratchet lever 94 released, the pawl 98 engages one of the

teeth 100. The ratchet mechanism engages successive teeth 100 as the handles 10, 12 are squeezed and prevents the handles from reopening. Depressing the finger portion 94a of the ratchet lever 94 disengages the pawl 98 from the ratchet teeth 100 and allows the handles 10, 12 to reopen. With the preferred construction, tension on a retaining ring can be maintained during installation and/or removal without effort by the operator. In use, the retaining ring is engaged by the jaws 16a, 16b (via the tips 19) and the handles 10, 12 are then squeezed to tension the retaining ring. As the handles are squeezed, the ratchet lever 94 engages the teeth 100 to maintain the position of the handles and prevent release of the retaining ring. When release of the retaining ring is desired, the ratchet lever 94 is depressed in order to disengage the pawl 98 from the teeth 100 enabling the handles to separate.

The present invention thus provides an inexpensive tool for removing and installing both internal and external retaining rings. The tool is easily switched between the internal and external modes and in particular the operating modes are changed by merely shifting the pair of latch members 30, 31 that cooperate with the jaw driving sections 26, 28 of the handles 10, 12 to selectively couple the jaw heads 16, 18 to the handles. A ratchet mechanism facilitates operation of the tool by preventing separation of the handles to maintain tension on a retaining ring held by the jaws 16a, 18a without substantial effort by the operator.

According to another feature of the present invention, a locking mechanism is provided for locking the tool handles and jaws in a closed position, as shown in the solid line drawing of FIG. 4. The locking mechanism includes a locking lever 94 pivotally connected to one of the handles 10, and having a locking position, also shown in the solid line drawing of FIG. 4. In the locked position, the locking lever engages the spring 90' and an end or coacting surface 44' to lock a pair of plier parts 204, 206 in the closed position.

In the preferred embodiment, the lock lever 94' is automatically movable from a locked position, to an unlocked position as best seen in FIG. 5. The lock lever is automatically moved from its locked position to an unlocked position under biasing action of the spring 90', when the handles, 10', 12', are moved from the closed position to a release position shown in the phantom drawing of FIG. 4.

In a preferred embodiment, the device includes an apertured locking lever 94' pivotally mounted on one handle section 10' by a lock pivot 200 projecting through a lever aperture 202. The lever 94' is pivotable between the lock and unlock positions and has a substantially triangular shaped body portion. In the illustrated embodiment, the lever is configured to minimize tool interference during operation and to avoid disengagement from the locked position upon movement or contact with other items during storage. The lever further comprises an engagement tab 98' for engagement with the coacting surface 44' of one plier part, indicated generally by reference character 204 in FIG. 4, when the lever 94' is in the locked position. The lever also includes a spring engaging surface 95' which is adapted for engagement with the coacting surface 44' of one plier part 204 when the lever is in the locked position. The coplanar engagement of the engagement tab 98' and coacting surface 44' is additionally maintained by the working association with the jaw heads 16', 18'. A finger engaging tab 94a' which extends from the lock

lever beyond and near to a side surface of one handle 10' is also featured in the illustrated embodiment. The finger engaging tab 94' provides for ease of manual pivoting of the lever 94' to the locked position.

The plier parts of the present invention are generally designated by reference characters 204 and 206 in the illustrated embodiment of FIG. 5. The plier parts comprise a pair of handles 10', 12' and jaw sections 16', 18', as shown in FIG. 3. A pair of pivotally connected boss sections or jaw driving sections 26', 28' interconnecting the jaw and handle sections are also included to provide the plier parts 204, 206. In the preferred arrangement the plier parts are capable of movement from the closed position to a release position upon compression of the handle sections 10', 12' against the spring 90'. As illustrated in FIG. 4, the boss section 26' of the first or second plier parts includes the coacting surface or end surface 44', coplanar with the lever and engageable with the engagement tab 98' when the plier parts 204, 206 are in the closed position. In an alternate embodiment, a selected portion of one plier part is located on a surface opposite and near to the front surface of one handle 10', having a coacting or end surface coplanar with the lever and engageable with the engagement tab 98' when the lever 94' is in the locked position.

During use, compression of the handle sections allows the lever to be pivoted into operative engagement with the coacting surface and spring biased into such engagement when the tool is in the closed position. The lever 94' is automatically pivotable out of engagement with the coacting surface 44' and spring 90' being biased to the unlocking position upon movement of the plier parts to the release position.

The embodiment of the tool shown in FIGS. 1-3 is constructed from stampings, the making of which is known by those skilled in the art. It should also be recognized that other relatively inexpensive methods of manufacture could be used to produce the disclosed tool and are all contemplated by the present invention. For example, one or more of the tool components such as the jaw head 16, 18 and/or the handles 10, 12 can be produced using powdered metal technology. It will be appreciated by those skilled in the art that, should the components be constructed of powdered metal, dimensional changes would have to be made to accommodate well known differences in the material characteristics of powdered metal as compared with stampings.

Although the invention has been described with a certain degree of particularity, it should be understood that various changes can be made to it by those skilled in the art without departing from the spirit or scope of the invention as hereinafter claimed.

I claim:

1. A snap ring plier tool including:
  - (a) pairs of handle and jaw sections;
  - (b) a pair of pivotally connected boss sections interconnecting the jaw and handle sections to provide a pair of plier parts;
  - (c) a spring interposed between the handles and biasing them toward an open position;
  - (d) one of the bosses including a coacting surface; and
  - (e) a lever pivotally connected to one of the handles and having a locking position engaging the spring and the coacting surface to lock the plier parts in a closed position.
2. The plier tool of claim 1 wherein the lever is a lock that is automatically moved from its locking position to an unlocked position under biasing action of the spring

when the lever has been in its locking position and the handles are moved from the closed position to a release position.

3. The plier tool of claim 1 wherein said one boss has a plurality of coacting surfaces and the lever is a ratchet lever whereby to provide a ratchet.

4. A plier tool comprising:

- (a) a pair of handle sections;
- (b) a pair of boss sections;
- (c) a pair of jaw sections;
- (d) a first section of each pair being operably connected together to function as a first plier part;
- (e) the second section of each pair being operably connected together to function as a second plier part;
- (f) a pivot interconnecting the first and the second plier parts for relative work performing movement between open and closed positions;
- (g) a spring operatively connected to and interposed between one of the first and one of the second sections for biasing the plier parts toward the open position;
- (h) a lever pivotally connected to a selected section and including an engagement tab, the lever being movable between plier open and closed positions;
- (i) another selected section having a coacting surface engageable by the engagement tab when the plier parts are in the closed position; and
- (j) said spring being in operative engagement with the lever at least when the plier parts are in the closed position and when the lever is in its locking position to bias the engagement tab against the coacting surface.

5. The plier of claim 4 wherein the lever is a lock lever.

6. The plier of claim 5 wherein the plier parts have a release position and wherein the spring biases the lever toward its unlocking position as the plier parts are moved from the closed to the release position.

7. The plier of claim 4 wherein the lever is a ratchet.

8. A plier tool comprising:

- (a) a pair of lever handle sections;
- (b) a pair of boss sections;
- (c) a pair of jaw sections;
- (d) a first section of each pair being operably connected together to function as a first plier part;
- (e) a second section of each pair being operably connected to function as a second plier part;
- (f) a pivot operatively interconnecting the first and second plier parts for relative work movement between open and closed positions;
- (g) a spring operatively connected to and adaptively interposed between the first and second sections for biasing the plier parts to the open position;
- (h) a locking lever pivotally mounted on a front surface of one handle section;
- (i) said lever being movable between locking and unlocking positions;
- (j) said lever having a substantially triangular shaped body portion;
- (k) said lever having an engagement tab for engagement with a selected portion of one of the plier parts when the lever is in the locked position;
- (l) said selected portion of the plier part being located on a surface opposite and near to the front surface of one handle section, and having a coacting surface coplanar with the lever and engageable with

11

- the engagement tab when the lever is in the locked position;
- (m) said engagement tab being formed to engage said coacting surface of the plier part when the lever is in the locked position;
- (n) said locking lever also including a spring engaging surface adapted for operatively engaging the spring when the lever is in the locked position;
- (o) said lever having a finger engaging tab extending from the lock lever beyond and near to a side surface of the handle section to provide for ease of manual pivoting engagement of the lever into the locked position;
- (p) said plier parts being capable of movement from the closed position to a release position upon compression of the handle sections against the spring; and
- (q) said lever being configured to minimize interference during operation and to avoid disengagement from plier locking position upon movement or accidental contact with other items.
9. A plier tool comprising:
- (a) a pair of lever shaped handle sections;
- (b) a pair of interlocking boss sections;
- (c) a pair of jaw sections;
- (d) a first section of each pair being operably connected together to function as a first plier part;
- (e) a second section of each pair being operably connected together to function as a second plier part;
- (f) a pivot operatively interconnecting the first and second plier parts for relative pivotal, work performing, variable movement between open and closed positions;
- (g) a spring operatively connected to and adaptively interposed between the first and second sections for biasing the plier parts to the open position;
- (h) an apertured locking lever pivotally mounted on one handle section by a lock pivot projecting through a lever aperture;
- (i) said lever being pivotally movable between lock- ing and unlocking positions;
- (j) said lever having a substantially triangular shaped body portion;
- (k) said lever also having an engagement tab for locking engagement with a selected portion of one plier part when the parts are in the closed position and the lever is in the locked position;
- (l) said selected portion of the plier part having a coacting surface coplanar with the lever and engageable with the engagement tab when the plier parts are in the closed position;
- (m) said locking lever also including a spring engaging surface adapted for operatively engaging the spring when the lever is in the locked position;
- (n) said lever having a finger engaging tab extending from the lock lever beyond and near to a side surface of the one handle section to provide for ease of manual pivoting engagement of the lever into the closed position;
- (o) said plier parts being capable of movement from the closed position to a plier release position upon

compression of the handle sections against the spring;

- (p) said lever being pivotable into operative engagement with said coacting surface and spring biased into such engagement when in the locking position, and automatically pivotable out of engagement with the coacting surface and spring biased to the unlocking position upon movement of the plier parts to the release position; and
- (q) said lever being configured to minimize interference with the lever during operation and avoid disengagement from the closed position upon movement or accidental contact with other items.

10. A retaining ring plier selectively for use with either internal or external rings comprising:

- (a) pivotably interconnected pairs of jaw and handle members;
- (b) each of said members including a boss;
- (c) a first two of the bosses including laterally extending guide surfaces;
- (d) a pair of slidably latch members each in slidable guided relationship with an associated one of the grooves;
- (e) a second two of the bosses each including a spaced pair of latch member engaging surfaces adapted selectively to engage an associated latch member whereby to provide member interconnection;
- (f) each of said latch members being movable in its slidably guided relationship between first and second member interconnected positions;
- (g) one of the jaws and one of the handles and the other of the jaws and the other of the handles being latch member interconnected when the latch members are in their first positions to provide an internal ring plier;
- (h) said one pair and said other handle and said other jaw and said one handle being respectively interconnected when the latch members are in their second positions to provide an external ring plier;
- (i) said latch members each having a first prong manually accessible when its latch member is in its first position to permit movement to the respective latch member second positions without resort to the use of a tool;
- (j) said latch members each including a second prong manually accessible when its latch member is in its second position to permit movement to the respective first latch member position without resort to the use of a tool;
- (k) a ratchet lever pivotally connected to one of the members; and
- (l) another of the members including a plurality of coacting surfaces which are sequentially engageable by a pawl to provide a ratchet.

11. The plier of claim 10 wherein a spring is interposed between the handles which spring applies biasing forces to the handles in a handle opening direction, said one member is a handle member and the pawl and spring are coactable.
